UNITED STATES PATENT OFFICE.

WILMOT CASTLE AND ARTHUR CASTLE, OF ROCHESTER, NEW YORK.

DESIGN FOR A RADIATOR.

SPECIFICATION forming part of Design No. 26,593, dated February 2, 1897.

Application filed December 31, 1896. Serial No. 617,658. Term of patent 7 years.

To all whom it may concern:

Be it known that we, WILMOT CASTLE and ARTHUR CASTLE, citizens of the United States, and residents of the city of Rochester, county 5 of Monroe, and State of New York, have invented and produced a certain new and useful Design for Radiators, of which the following is a specification, reference being had to the accompanying drawing, which represents 10 an elevation of a radiator embodying our design.

The distinctive features of our design are hereinafter described, and pointed out in the 15 claim, and consist in the contour and ornamentation of the top and base pieces and in the combination of these top and base pieces with the connecting-columns.

The top piece A has a top in a horizontal plane and a depending ogee edge, upon which 20 is a band *a*, consisting of the arabesque

scrolls arranged symmetrically with reference to the middle vertical line thereof upon the convex portion of the ogee. The base-piece B is similar to the top piece A and has a band *b* upon it with like arabesque scrolls. The 25 legs C, depending from the base-piece B, have the radiating ornaments *c*.

Between the base-piece B and the top piece A are a series of columns D, having depressions or indentations symmetrically arranged 30 upon their convex surfaces. The arrangement of these depressions is quincuncial.

What we claim is—

The design for a radiator, substantially as herein shown and described.

WILMOT CASTLE.
ARTHUR CASTLE.
